[57] CLAIM

The ornamental design for compact fluorescent bulb socket, as shown and described.

DESCRIPTION

FIG. 1 is an exploded perspective view of the compact fluorescent bulb socket of the present invention with a securing ring separate from a body of the socket;

FIG. 2 is a perspective view of the compact fluorescent bulb socket with the securing ring threaded onto the socket body;

FIG. 3 is an exploded side elevational view of the socket;

FIG. 4 is an exploded side elevational view of the socket rotated 90° from FIG. 3;

FIG. 5 is a side elevational view of the compact fluorescent bulb socket with the securing ring threaded onto the socket body, all side elevational views of the assembled socket being identical;

FIG. 6 is a top plan view of the compact fluorescent bulb socket; and,

FIG. 7 is a bottom plan view of the fluorescent bulb socket. The broken line showing in FIGS. 1, 2, 6 and 7 is included for the purpose of illustrating environmental structure only and forms no part of the claimed design.
